United States Patent Office.

ORION FRAZEE, OF NEW YORK, N. Y.

Design No. 2,536, dated January 1, 1867.

DESIGN FOR A MEDALLION.

The Schedule referred to in these Letters Patent and making part of the same.

TO ALL WHOM IT MAY CONCERN:

Be it known that I, ORION FRAZEE, of the city, county, and State of New York, have invented a new and "Improved Design for a Medallion;" and I do hereby declare that the following is a full, clear, and exact description thereof, which will enable others skilled in the art to understand the same, reference being had to the accompanying drawing, forming part of this specification.

The present invention relates to a new design for a medallion of the head and shoulders of Andrew Jackson, ex-President of the United States, which design is illustrated in the accompanying plate by a photographic view of the same.

The head, A, is in side or profile view, with the body or shoulders, B, turned somewhat to the front, and so as to be in angular position with reference to the head, the design embracing the body sufficiently to show a portion of the shirt bosom, C, and coat, D.

Having thus described my invention, I claim as new, and desire to secure by Letters Patent—

The design for a medallion herein described and shown in the accompanying plate.

The above specification of my invention signed by me this 14th day of July, 1866.

ORION FRAZEE.
